CLAIM

We claim the ornamental design for a dinosaur-shaped animal toy, as shown and described.

DESCRIPTION

FIG. 1 is a perspective view of a first embodiment of a dinosaur-shaped animal toy showing our new design.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1.

FIG. 7 is a bottom plan view of FIG. 1.

FIG. 8 is a perspective view of a second embodiment of a dinosaur-shaped animal toy showing our new design.

FIG. 9 is a front elevational view of FIG. 8.

FIG. 10 is a rear elevational view of FIG. 8.

FIG. 11 is a left side elevational view of FIG. 8.

FIG. 12 is a right side elevational view of FIG. 8.

FIG. 13 is a top plan view of FIG. 8; and,

FIG. 14 is a bottom plan view of FIG. 8.

The broken lines in the figures represent portions of the dinosaur-shaped animal toy that form no part of the claimed design.
